UNITED STATES PATENT OFFICE.

HENRY LOTZ, OF PROVIDENCE, RHODE ISLAND, ASSIGNOR TO THE LOTZ PROTECTOR AND SALVAGE COMPANY, OF PROVIDENCE, RHODE ISLAND, A CORPORATION OF RHODE ISLAND.

MARKING DEVICE FOR SUNKEN VESSELS.

1,238,538.

Specification of Letters Patent. Patented Aug. 28, 1917.

Application filed December 23, 1916. Serial No. 138,552.

To all whom it may concern:

Be it known that I, HENRY LOTZ, a subject of the Czar of Russia, residing at Providence, in the county of Providence and 5 State of Rhode Island, have invented certain new and useful Improvements in Marking Devices for Sunken Vessels; and I do hereby declare the following to be a full, clear, and exact description of the invention, such as will enable others skilled in 10 the art to which it appertains to make and use the same.

This invention relates to improvements in marking devices for sunken vessels.

15 The object of the present invention is to improve the construction of marking devices for sunken vessels and to provide a simple, practical and efficient marking device of strong, durable and comparatively 20 inexpensive construction designed for use in connection with a device for hoisting safes from sunken vessels shown and described in a companion application executed by me of even date herewith.

25 A further object of the invention is to provide a marking device of this character adapted to be arranged upon a vessel exteriorly of the same so as to float off of the vessel in event of the sinking of the vessel 30 and capable of assuming an upright position in the water and of automatically closing a circuit for causing an electric lamp to glow, so that the marking device may be seen at night as well as in the day time.

35 With these and other objects in view, the invention consists in the construction and novel combination of parts hereinafter fully described, illustrated in the accompanying drawing and pointed out in the claims 40 hereto appended; it being understood that various changes in the form, proportion, size and minor details of construction, within the scope of the claims, may be resorted to without departing from the spirit or sacrificing any of the advantages of the invention.

In the drawing:

Figure 1 is a side elevation of a marking device constructed in accordance with this 50 invention and shown arranged in position for automatic operation.

Fig. 2 is an enlarged vertical sectional view illustrating the arrangement of the parts of the marking device when the latter 55 is in an upright position.

Like numerals of reference designate corresponding parts in all the figures of the drawing.

In the accompanying drawing in which is illustrated the preferred embodiment of the 60 invention, the marking device comprises in its construction a buoy 1 consisting of a hollow tapering body or shell of suitable material rounded at the bottom at 2 and having a truncated upper end 3 upon which is 65 mounted an electric light 4 rotated within a protecting cage 5 and a suitable globe 6 of glass or other transparent material and which may be of any desired color and which may contain any suitable indicating 70 mark for identifying it with a vessel with which it is connected. The shell is provided at the bottom with spaced eyes 7 and it is designed to be connected with a guide rope or line 8 having branches 9 secured to the 75 said eyes. The guide line 8 is designed to extend to the coupling member of the aforesaid application but the buoy or marking device may be employed in connection with other means for connecting it with a sunken 80 vessel or other spot or object to be marked as will be readily understood.

The electric light is connected by suitable conducting wires or conductors 10 and 11 with a battery 12 and with a contact 13. A 85 conducting wire 10 is secured to one of the poles of the battery 12 and the other pole of the battery is connected by a wire or conductor 14 with a contact 15. The contacts 13 and 15 are located in opposite sides of 90 a downwardly tapered depending vertical terminal portion 16 of an inclined tube 17 forming a guide for a ball 18 normally located at the outer end of the tube in the dotted line position of Fig. 2 when the buoy or 95 marking device is arranged in the horizontal position as illustrated in Fig. 1. When in this position the tube extends downwardly but when the buoy assumes an upright position in the water the tube is placed in an 100 inclining position and the ball rolls down the inclined tube and establishes an electrical connection between the contacts 13 and 15. The ball may be of any suitable metal and while the movable contact member or 105 ball is preferably round as shown it may be of any other desired form. The tube is provided at its outer end with a removable closure 17' preferably in the form of a plug and the shell or body of the buoy is pro- 110

vided with a manhole or hand hole 18 and a suitable closure 19 for the frame.

A battery is arranged in a suitable support composed of spaced members 20 and 5 extending above and adapted to support the battery out of contact with the guide tube. The spaced supports are connected with the sides of the shell by suitable braces 21 and the upper portion of the body of the shell 10 is preferably braced by rods or bracing members 22 having a plurality of crossed inclined bracing portions arranged at an angle and secured to the shell at opposite sides thereof at the terminals of the inclined portions. By this construction the shell may be made of relatively light material and will be sufficiently strong to prevent it from being accidentally injured by pieces of a wreck. The hollow shell or body is of sufficient 20 length so that the weight of the body will maintain the buoy in a horizontal position upon a horizontal surface and the rounded bottom of the body will prevent the same from being accidentally placed in an upright 25 position and thereby consuming the energy of the battery unnecessarily. The hollow shell body may of course be flattened at the bottom to enable it to be placed in an upright position if desired.

30 What is claimed is:—

1. A marking device for sunken vessels including a hollow tapered buoy having a rounded bottom portion adapted to prevent it from being placed in an upright position 35 on a supporting surface, an electric circuit having spaced contacts, an electric light arranged in the said circuit, a battery also connected in the said circuit, an inclined guide extending to the spaced contacts and 40 a movable contact mounted in the guide and arranged to be directed to the spaced contacts by the guide when the buoy is in an upright position and maintained out of engagement with the said contacts by gravity

when the buoy is placed in a horizontal position. 45

2. A marking device of the class described including a buoy consisting of a hollow tapered shell truncated at one end and rounded at the other, an electric circuit arranged 50 within the buoy, an electric light mounted on the truncated end of the buoy, means contained within the buoy for guiding a movable contact into engagement with the spaced contact when the buoy is arranged in an 55 upright position, a globe covering the electric light and the cage secured to the buoy and retaining the globe in position.

3. A marking device for sunken vessels including a hollow buoy, an electric circuit 60 contained within the buoy and having spaced contacts, an electric light arranged in the said circuit, an inclined guide tube extending from one side of the buoy downwardly and inwardly and having a terminal portion 65 carrying the said spaced contacts, a movable contact operating within the said tube and a closure for the outer end of the tube.

4. A marking device for sunken vessels including a hollow tapered shell rounded 70 at the bottom and provided thereat with means for connecting a line to the shell, bracing members extending longitudinally of the shell and having oppositely inclined 75 crossed portions secured at their terminals to the flange of the shell, an electric circuit contained within the shell and provided with means for automatically closing it when the shell is in an upright position and an electric light carried by the shell and arranged in the said circuit. 80

In testimony whereof I affix my signature in presence of two witnesses.

HENRY LOTZ.
